UNITED STATES PATENT OFFICE.

WILLIAM P. McLAUGHLIN, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,104,209.

Specification of Letters Patent. Patented July 21, 1914.

Application filed May 13, 1911. Serial No. 627,026.

To all whom it may concern:

Be it known that I, WILLIAM P. McLAUGHLIN, a citizen of the United States, residing in borough of Brooklyn, city of New York, 5 in the county of Kings and State of New York, have invented certain new and useful Improvements in Type-Writing Machines, of which the following is a specification.

The invention relates to an improved 10 tabulating mechanism for typewriting machines.

The object of the invention is to combine 15 in a single machine a decimal tabulating mechanism and a column skipping mechanism, both operable from a single set of keys, so that, by the operation of one key, the carriage may be released, and caused not only to skip one or more columns to reach the desired column in a single movement, but to 20 be arrested at any desired decimal position in the column to which the carriage is skipped.

The invention comprises as a feature thereof 25 an adjustable carriage stopping mechanism for each column, each of these stopping mechanisms being adjustable by one column key to arrest the carriage at any desired decimal position of the selected column, and each of these mechanisms being ineffective 30 to arrest the carriage at all unless the proper column key is operated.

In the embodiment of the invention hereinafter specifically described, the adjustable carriage stopping mechanisms for the several columns are shown as groups of stops, 35 preferably vertical sliding rods, the number of stops in each group being equal to the number of decimal positions in the column; and the adjustment consisting in selecting, 40 by means of the column key, the desired stop of each group; so that thereafter, by another or further movement of the key, the selected stop of the group is set to arrest the carriage at the column represented by it.

In the preferred form of the invention, 45 the stops of each group are arranged in a row, the rows being parallel to each other and to the line of movement of the carriage. The column key levers are progressively 50 lengthened so that each may reach the row of stops controlled by it; and, in order that each lever may coöperate with any stop in its row or group, the levers are mounted not

only to have a downward movement for projecting the stops, but also to have a lateral 55 swing or stop selecting movement.

The manner in which the keys are mounted; the means for assuring the proper stop selecting movement of the same, and the means for returning the keys to a normal setting are more or less important features of the invention. The invention in the form shown also comprises a series of racks, one for each group of stops all carried by the carriage; and, adapted to be set in any 60 desired column position on each rack, is a column stop or plug for coöperation with the key selected stop of the group corresponding to that rack.

It is a feature of the invention that the 70 mechanism may be employed as a decimal tabulator, with the column skipping feature eliminated; and that in this use of the invention, any one of the column keys may be used repeatedly to move the carriage from one 75 column to the next, the decimal stopping position in each column being determined as before by the key adjustment or stop selecting operation, before the key is depressed.

Other features of the invention will hereinafter appear.

In the accompanying drawings, Figure 1 is a perspective view of the assembled parts as applied to an Underwood typewriter. 85 Fig. 2 is a side view of the mechanism looking from the right of the machine, the parts being in normal or inactive position. Fig. 3 is a view similar to Fig. 2 except that the parts are in the position assumed when one of 90 the column keys is depressed. Fig. 4 is a top plan view of the lever system showing the normal relation of the same to the stops. Fig. 5 is a detail view illustrating the manner of mounting the keys.

The invention is shown as applied to an Underwood typewriter. The carriage 1 is driven in letter feed direction from the usual spring drum 2 by the strap 3. The letter feed movement is controlled by an 100 escapement wheel 4, which carries a pinion 5 meshing with a rack 6, the latter being supported from the carriage, at each end of the same, by means of an arm 7. The escapement wheel 4 is controlled in the usual manner by an escapement device 8 operated from 105

the type keys. To permit the carriage to be thrown independently of the escapement mechanism, provision is made for disengaging the escapement rack from the pinion 5 with which it normally meshes; and to this end, the arms 7 by which the rack is carried are pivoted to the carriage as at 9, one of the arms being extended to carry the release key 10. Depression of the key 10 causes the rack to be lifted out of engagement with the escapement pinion 5, thus releasing the carriage. The rack 6 when in normal position rests and moves upon a roller 11 which serves as a frictionless bearing and also as a means for maintaining the proper intermeshing relation of rack and escapement pinion.

In addition to the key 10 for releasing the carriage from the escapement mechanism, 20 the carriage may be released from any one of a number of column stop keys 12. These keys are shown in the drawings as five in number, each representing a column position, but may be of any number desired. 25 The keys 12 are carried by levers 13 pivoted between frame members 14 and 15 and having arms 16 which extend to the rear of the pivots. For releasing the carriage from the keys 12, the following means is provided. Crossing each of the arms 16 is a bar 17 which is integral with and is supported from two vertical arms 18. The arms 18 are pivotally attached to arms 19 which are made integral by a cross bar 20 and are connected to a sleeve 21, which is fast to a rock shaft 22 mounted in brackets 22^a. Also fast to the rock shaft 22 is a lever arm 23, connected by a link 24 with a lever 25 pivoted at 26 to the frame. The 40 forward arm of the lever 25 carries the roller 11 on which the escapement rack 6 rests. When any one of the keys 12 is depressed, the corresponding key lever arm 16 raises the bar 17, and with it, the push rods 45 or arms 18, thus causing the shaft 22 to be rocked. This movement of the shaft causes the link 24 to be drawn down, and the lever 25 to be rocked in such manner as to lift the roller 11 with the rack until the latter is 50 free of the escapement pinion 5, and the carriage thus released to the action of the drum spring. In order that the movement of the carriage when thus released may not be too violent, there is provided a suitable 55 braking device or governor, inclosed in a casing 27, for checking the throw of the carriage. The governor acts on the spring drum through a bevel gear 28 on the governor and a bevel gear 29 on the spring drum 2. These gears are ordinarily out of mesh (see Fig. 2) so that normally the drum is free of the governor. The governor is mounted on the rock shaft 22, and the latter in moving to lift the rack to release the 60 carriage, rocks the gear 28 into engagement

with the gear 29 on the drum (see Fig. 3), so that when the carriage is released, it is under the control of the governor. The movement of the keys 12 is limited by the bar 45 at the front of the machine, and the 70 movement of the carriage releasing and governing mechanisms may also be limited by the engagement of the escapement rack with the carriage frame above the same as shown in Fig. 3, or by other suitable stops. A 75 coil spring 30 on the rock shaft by engagement at one end with one of the brackets 22^a; and at the other end with the sleeve 21, returns the rock shaft and all connected parts to normal position when the key is 80 released. The weight of the rack returns it to the escapement pinion, and assists in the return of the other parts. The key itself is returned by the coil spring 30, acting through the bar 17; and the keys on striking the frame bar 60 at the front of the machine finally determine the return movement of the other parts.

As heretofore stated, there is combined in the present invention a column selecting 90 mechanism, and a decimal tabulating mechanism. These mechanisms comprise a number of column stops suitably secured to the carriage and adapted to be adjusted thereon to predetermined positions, and a set of 95 movable key controlled counter stops which, when actuated, coöperate with the column stops to arrest the carriage in the desired positions. The movable stops whether used for column selecting, or for decimal tabulating purposes, are controlled from a single 100 set of keys 12 of which there are five shown in the drawings, but which may be of any desired number. These keys are preferably located at the front of the keyboard, as 105 shown in Fig. 1, and are numbered "I" to "V" respectively, key "I" representing the first column position, key "II" representing the second column position, etc. Each of the keys "I" to "V," controls a correspondingly numbered row or bank of counter stops 32, preferably in the form of vertically disposed sliding rods, each counter stop having independent vertical movement in a casing 33 secured to the main frame of 115 the machine. In Fig. 1 these counter stops are shown with their upper ends flush with the top 33^a of the casing 33 when in normal or depressed position. The rows "I" to "V" of counter stops are shown as parallel 120 to the line of feed of the carriage. The rearmost row "I" of stops 32 is controlled by the "I" key; the next row by "II" key; etc., the front row "V" being controlled by the "V" key. When any one of the stops 32 is operated by its proper key it is forced upward above the top surface 33^a of the casing 33.

Attached to the rear of the typewriter carriage is a plate 34 having therein five 130

rows, numbered "I" to "V," of perforations or pin holes 35, spaced ten to the inch, or otherwise, according to the pitch of the letter feed movement of the carriage. Each row of holes is in effect a rack. The rows of pin holes extend parallel to the direction of movement of the carriage, and each row or rack is alined with one of the rows of stops 32. If more than five keys 12 are employed, there will be a corresponding increase in the number of racks or of rows of pin holes. The plate 34 being secured to the carriage moves back and forth as a unit with the latter. There are shown a number of plugs or stop pins 36, which are suitably positioned in the perforations of the plate 34, in accordance with the desired column positions of the carriage. The column stops 36 project below the plate 34; and the upward movement of the stops 32, when the latter are actuated, is sufficient to cause the elevated stop to intercept the path of any plug 36 which may be in a row of pin holes alined with the stop so elevated, so that when a plug in that row is brought by the movement of the carriage to the elevated stop, it strikes the same and arrests the carriage. Each of the stops 32 thus forms a counter stop for the column stop 36 in the corresponding row in the plate 34.

The carriage when released continues its movement until some one of the plugs 36 strikes an elevated stop 32. According, therefore, to which of the keys 12 is operated, the movement of the carriage after release of the same may be from one column to the next column, or may involve the skipping of one or more of the succeeding columns, before the carriage is again arrested. Obviously any one of the five stops 32 in a row, when operated, will coöperate with any plug or pin which may be in the corresponding row of perforations, and the stopping position of the carriage in a given column will depend upon which of the five alined stops is operated. The right hand stop of a row will arrest the carriage sooner than will a stop farther to the left in the same row. The spacing of the stops in each row is equal to the pitch of the letter feed movement of the carriage; so that, assuming the first stop to the right in a row to be the stop for arresting the carriage at the "thousands" position of a column, the next stop of the same row will arrest the carriage at the "hundreds" position; the next at the "tens;" the next at the "units;" and the last one to the left, at the decimal point position. The first stop to the right may of course be used as the decimal point stop, and those to the left as the tenths, hundredths, etc. The column stops 36 are usually so positioned as to coöperate with the left hand counter stop 32 to arrest the carriage at the decimal point position when the left hand

counter stop for any particular column is actuated by that key 12 which represents the selected column.

It has been stated that each of the keys 12 is adapted to operate the counter stops of some one row. The means by which the keys control the counter stops, and are adjustable to select any counter stop of the row controlled thereby are as follows: The rear arm 16 of the key lever of key "V" (see Fig. 4) terminates under the forward or "V" row of stops 32, and is slightly bent or offset, so that, with the key "V" in the position shown in Fig. 4, the end of the key lever is under the left end stop 32 of row "V," this being ordinarily the decimal point stop of that row. Lever arm 16 of key lever "IV" is bent or offset more than arm 16 of lever "V," so as to be extended beyond the same, and has a lateral extension 37 to bring the end of this lever under the stops of row "V" of the stops. The lever arms of keys "III," "II" and "I" are progressively offset and extended, and have progressively longer lateral extensions 37, so that when all of the keys are in Fig. 4 position the ends of the key levers are alined under the left end or decimal point stops of the respective rows of plungers. At the end of each of the lateral extensions 37 is an upward projecting tooth 38 for coöperation with the feet of the counter stops 32. These feet are preferably provided with V-shaped recesses 40, and the teeth 38 are correspondingly shaped, so that the engagement and centering of tooth and plunger foot, when the key is operated, may be true.

In order that the key levers may be made to engage not only the left end stops of the respective rows, but any stop of that row, the key levers are mounted in the cross pieces 14 and 15 in such manner as to be capable not only of vertical but also of lateral swing. This universal mounting of the key levers is shown in Fig. 5. Each lever 13 is shown fitted within a slot 41 in a spool 42, and mounted on a horizontal pivot pin 43 carried by the spool, so as to have movement in a vertical plane, the slots being sufficiently long to permit of this movement. Each spool is held at top and bottom by set screws 44 which project through the cross pieces 14 and 15, and have pointed ends fitted within corresponding recesses in the top and bottom of each key lever. The tips of the screws serve as cone bearings on which the spools are adapted to turn, so that the key levers may be swung to right and left, and their ends therefore brought under any selected stop of the corresponding row of stops.

In the frame plate 45 at the front of the machine, and under each key, is a comb 46, between the teeth 47 of which are slots or spaces 48 of sufficient width to receive the key levers. The keys are normally held ele-

vated as heretofore mentioned, so that the key levers are out of the slots 48 (see Fig. 1), and when in such position the key levers lie in the space between the teeth of the 5 comb and the bar 60. Springs 49 secured to the cross piece 14 by means of the upper screws 44, bear aginst the sides of the key levers, and in so doing act to throw the keys to the right until this movement is arrested by the shoulders 50 of the plate 45, 10 in which position each key lever is over the right end slot 48 of its comb, with its tooth 38 at its other end under the left end or decimal point stop. Depression of a key 15 when in such position, effects the operation of the corresponding decimal stop, which will be considered as the decimal point stop. If it be desired to operate the stop immediately to the right of the decimal point stop, 20 the key is moved to the left against the action of its spring 49, until the key lever lies over the next slot 48, this movement causing the tooth 38 at the other end of the lever to move to the right until it lies under the next 25 adjacent stop; whereupon the key lever is depressed into the slot 48 below the same, and the tooth elevated to raise the stop. There is a slot 48 for each stop 32, and these slots serve to determine accurately the position 30 of the tooth 38 with respect to the stop feet. The slots are shown as marked to indicate the decimal position represented thereby. The teeth 47 of the comb are pointed, as shown in Fig. 1, so that the key 35 levers may be readily guided into the proper slots. No matter into what slot 48 the lever may be pressed, or what stop it may have operated, whenever released it will first be thrown up to be disengaged from the comb, 40 and will then be thrown to its normal right hand position by its spring 49.

Secured at one end to hooks 51 on the stops 32 and at the other end to cross pieces 53 on the tabulator frame are coil springs 45 52 which serve to return the stops 32 to normal position when the keys are released. The springs 52 and cross pieces 53 are arranged in tiers so that space enough for the springs may be provided. The arrangement 50 of springs is as shown in Fig. 1. The five springs at the front take care of the five stops of row "V." Row "I" is taken care of by five similarly arranged springs at the rear of the casing. The three right end 55 stops of rows "II," "III" and "IV" are connected to the lower three springs on the right hand side of the casing; and the left end stops of rows "II," "III" and "IV" are connected to three springs in a lower 60 tier on the left hand side of the casing. This leaves the three central stops of rows "II," "III" and "IV," or nine in all; five of which are reached from the five upper springs on the right hand side by means of 65 hooks which pass in between the rows of

stops 32; and the four remaining stops 32 are reached from a similar upper row of four springs by means of hooks which pass in between the rows of stops from the left hand side. The springs 52 assist the spring 70 30 in the return of the key levers to normal position. Stops 55 in the form of studs which extend through the casing 33 from right to left serve to determine the normal position of the stops 32, and may also limit 75 the upward throw of the same. The opposing faces of rows "V" and "IV" of the stops 32, and of rows "III" and "II" are cut or recessed at 56 to form elongated pockets through which the stops 55 are passed. The stops 55 are of such size that the shoulders 57 formed by the recesses in the opposing stops 32 may all strike the stops 55, to arrest the movement of the stops 32 at the appropriate time. Two stops 55 therefore 80 take care of four of the rows of stops 32. Another stop 55 serves the first row in the same manner.

The following is a résumé of the operation of the machine: The column stops 36 90 are first set in the plate 34 in the positions which have been selected for the columns, and the carriage being thrown to starting position, the machine is ready for writing. If there is writing to be done in the first 95 column, the first key 12 to be operated is key "I." If the left hand stop 32 (ordinarily the decimal point stop) represents the desired stopping position in the first column, then key "I" is simply depressed; otherwise it is first swung to the left until over that particular comb slot 48 which represents the desired decimal stopping position, the tooth 38 on the end of the key lever being thus brought under the selected decimal stop. The key now being depressed, releases the carriage from the escapement mechanism, throws in the governor, and simultaneously elevates the selected stop 32 of the rear row "I" of stops alined with 100 that column stop 36 which is set in the rear row of holes 35. The carriage when released moves with the plate 34 until the column stop 36 of row "I" strikes the elevated stop, whereupon the carriage is 110 arrested. On release of the key, the escapement rack falls back into engagement with the escapement pinion; the spring 30 throws out the governor and acts through the bar 115 17 to return the key 12 to elevated position; the spring 52 throws down the previously elevated stop 32; and, as soon as the key has been lifted out of its comb, its spring 49 throws it to the right against its stop shoulder 50. The type keys are then operated for the writing of column "I"; and, the writing in column "I" being finished, the column key for the next desired column is operated. Obviously the carriage will not 120 stop at column "I," or any column, unless 125 130

some one stop 32 in the corresponding row of stops is elevated. Consequently the carriage when once released will not stop until reaching the column controlled by whichever of the keys 12 may be depressed. All 5 columns controlled by keys ahead of the depressed key will be skipped by the carriage, and the carriage will always come to rest at a decimal position of the selected 10 column, as determined by the preliminary adjustment of the key over the comb slots 48.

The machine may be used as a decimal tabulator, with the column skipping feature eliminated, and in such cases, the plugs 36 15 may all be set in some one of the several rows of plug holes, no matter which, and only the key 12 which controls the corresponding row of stops 32 need then be operated. When the machine is used in this 20 manner, the same key will be depressed to release the carriage after each column is written; and, since the plugs are now all aligned, the carriage will always be arrested at the next column by the first on-coming 25 plug 36. The decimal stopping position in each column will be determined in each instance, as heretofore described, by the adjusted position of the key over the slots 48 before the key is depressed.

30 The structure described is susceptible of considerable modification within the scope of the invention.

Having thus described my invention, I claim:

35 1. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by the group, and a key controlling each group of stops.

2. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by the group, and a key controlling each group of stops; the stops of each group being normally ineffective to arrest the carriage, so that columns may be skipped in which no one of the stops is operated.

3. In a typewriting machine, the combination of a power driven carriage, an es-

capement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by the group, a number of racks, one for each group of stops carried by the carriage, stops adjustable to fixed positions on said racks, and a key controlling each of said groups of movable stops to project any selected stop in a group into the path of the fixed stop on the rack which co-operates with that group.

4. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by the group, the stops of each group being arranged in the direction of movement of the carriage and each stop of a group being a letter space in advance of the preceding stop, a number of racks arranged parallel to the direction of movement of the carriage, stops adjustable to fixed positions on the racks, and a key controlling each group of movable stops to project any selected stop of a group into the path of the fixed stop on one of the racks.

5. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by the group, keys corresponding in number to the number of groups of movable stops, means whereby each key may be moved to register with any stop in a group, and means whereby said key may then be moved to actuate the stop with which it registers.

6. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a

- group representing some one decimal stopping position in the column represented by the group, keys corresponding in number to the number of groups of movable stops, 5 means whereby each key may be moved laterally to register with any stop in a group, and means whereby said key may then be depressed to actuate the stop with which it registers.
- 10 7. In a typewriting machine, the combination of a power driven carriage, an escapement mechanism for controlling the letter feed movement of the carriage, means for releasing the carriage from the escapement 15 mechanism to permit the carriage to run from one column position to another, a plurality of groups of movable stops, one group for each column, and each stop in a group representing some one decimal stopping position in the column represented by the group, and a key controlling each group of stops; the levers of said keys being mounted on universal joints to permit of a preliminary setting of the keys for any stop of a 20 group, and of another movement of the keys 25 for actuating the selected stop.
8. In a typewriting machine, the combination of a power driven carriage, an escapement mechanism for controlling the letter 30 feed movement of the carriage, means for releasing the carriage from the escapement mechanism to permit the carriage to run from one column position to another, a plurality of groups of movable stops, one group 35 for each column, and each stop in a group representing some one decimal stopping position in the column represented by the group, a key controlling each group of stops; the levers of said keys being mounted on 40 universal joints to permit of a preliminary setting of the keys for any stop of a group, and of another movement of the keys for actuating the selected stop, said universal 45 joints comprising bearing blocks in which the key levers are pivoted to have vertical 50 movement, and means whereby said bearing blocks may be swung around a vertical axis, whereby the keys may first be set for a selected stop and thereafter operated to actuate that stop.
9. In a typewriting machine, the combination of a power driven carriage, an escapement mechanism for controlling the letter feed movement of the carriage, means 55 for releasing the carriage from the escapement mechanism to permit the carriage to run from one column position to another, a plurality of groups of movable stops, one group for each column, and each stop in a 60 group representing some one decimal stopping position in the column represented by the group, keys corresponding in number to the number of groups of movable stops, means whereby each key may be moved to register 65 with any stop in a group, means whereby said key may then be moved to actuate the stop with which it registers, and a comb-like member over the top of which the key lever is adapted to be swung in setting the key for a particular stop and between the teeth of which the key lever is adapted to be depressed to determine the correct setting of the key for actuating the selected stop.
10. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by the group, keys corresponding in number to the number of groups of movable stops, means whereby each key may be moved to register with any stop in a group, means whereby said key may then be moved to actuate the stop with which it registers, and a comb-like member over the top of which the key lever is adapted to be swung in setting the key for a particular stop and between the teeth of which the key lever is adapted to be depressed to determine the correct setting of the key for actuating the selected stop.
11. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by the group, keys corresponding in number to the number of groups of movable stops, means whereby each key may be moved to register with any stop in a group, means whereby said key may then be moved to actuate the stop with which it registers, and a comb-like member over the top of which the key lever is adapted to be swung in setting the key for a particular stop and between the teeth of which the key lever is adapted to be depressed to determine the correct setting of the key for actuating the selected stop; the teeth of said comb being pointed to guide the key lever to centered position.
12. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by the group, keys corresponding in number to the number of groups of movable stops, means whereby each key may be moved to register with any stop in a group, means whereby said key may then be moved to actuate the stop with which it registers, and a comb-like member over the top of which the key lever is adapted to be swung in setting the key for a particular stop and between the teeth of which the key lever is adapted to be depressed to determine the correct setting of the key for actuating the selected stop; the slots or spaces between the comb teeth being marked to indicate decimal positions corresponding to the stops of the group.
13. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by the group, keys corresponding in number to the number of groups of movable stops, means whereby each key may be moved to register with any stop in a group, means whereby said key may then be moved to actuate the stop with which it registers, and a comb-like member over the top of which the key lever is adapted to be swung in setting the key for a particular stop and between the teeth of which the key lever is adapted to be depressed to determine the correct setting of the key for actuating the selected stop.

- from one column position to another, a plurality of groups of movable stops, one group for each column, and each stop in a group representing some one decimal stopping position in the column represented by the group, keys corresponding in number to the number of groups of movable stops, means whereby each key may be moved laterally to register with any stop in a group, means 5 whereby said key may then be depressed to actuate the stop with which it registers, and a spring for throwing each key laterally to a normal setting when the key is released. 10
13. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by 15 the group, keys corresponding in number to the number of groups of movable stops, means whereby each key may be moved laterally to register with any stop in a group, means whereby said key may then be depressed to actuate the stop with which it registers, and a spring for throwing each key laterally to a normal setting when the key is released. 20
14. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by 25 the group, keys corresponding in number to the number of groups of movable stops, means whereby each key may be moved laterally to register with any stop in a group, means whereby said key may then be depressed to actuate the stop with which it registers, and means for elevating and for swinging each key laterally to a normal setting when the key is released. 30
15. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by 35 the group, keys corresponding in number to the number of groups of movable stops, means whereby each key may be moved laterally to register with any stop in a group, means whereby said key may then be depressed to actuate the stop with which it registers, and means for throwing each key when released to a normal setting with respect to one of the movable stops. 40
16. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by 45 the group, keys corresponding in number to the number of groups of movable stops, means whereby each key may be moved laterally to register with any stop in a group, means whereby said key may then be depressed to actuate the stop with which it registers, a comb-like member over the top of which the key lever is adapted to be swung in setting the key for a particular stop and between the teeth of which the key lever is adapted to be depressed to determine the correct setting of the key for actuating the selected stop; means whereby the key levers when released are thrown out of the comb, and means whereby the key levers when disengaged from the comb are swung laterally over the comb to normal setting. 50
17. In a typewriting machine, the combination of a power driven carriage, an escapement mechanism for controlling the letter feed movement of the carriage, means for releasing the carriage from the escapement mechanism to permit the carriage to run from one column position to another, a plurality of groups of movable stops, one group for each column, and each stop in a group representing some one decimal stopping position in the column represented by 55 the group, the stops of each group being arranged in the direction of movement of the carriage and each stop of a group being a letter space in advance of the preceding stop, a number of racks by the carriage and having therein a plurality of rows of plug holes, one row for each group of the said movable stops, said rows of holes being ar- 60

- ranged parallel to the direction of movement of the carriage, stops or plugs adjustable to fixed positions in the several rows of holes, and a key controlling each group of said movable stops to project any selected stop of a group into the path of the plug in the corresponding row of holes.
18. In a typewriting machine, the combination of a power-driven carriage, an escapement mechanism for controlling the letter-feed movement of the carriage, means for releasing the carriage from the escapement mechanism to permit the carriage to run from one column position to another, a plurality of groups of movable stops, one group in each column, and each stop in a group representing one decimal stopping position in the column represented by the group, the stops of each group being arranged in the direction of movement of the carriage and each stop of a group being a letter space in advance of the preceding stop, a number of keys by the carriage and having thereon a plurality of rows of plug holes, one row for each group of the movable stops, the holes in each row being spaced five letter-spaces in advance of the travel of the carriage, said rows of holes being arranged parallel to the direction of movement of the carriage, stops or plugs adjustable to fixed positions in the several rows of holes, and a key controlling a plurality of movable stops to project any selected stop of a group into the path of the plug in the corresponding row of holes.
19. In a typewriting machine, the combination of a carriage and a series of groups of stops arranged on the carriage for each of said groups, and a single key for selectively projecting the stops of each of said groups.
20. In a typewriting machine, the combination of a power-driven carriage, an escapement mechanism for controlling the letter-feed movement of the carriage, means for releasing the carriage from the escapement mechanism to permit the carriage to run from one column position to another, a plurality of column stops arranged along several lines of holes of the carriage, each line of holes of the carriage being a single line of holes defining a group of stops, each stop of said group being adjustable to project into any one of a plurality of fixed positions in the direction of movement of the carriage.
21. In a typewriting machine, the combination of a travelling carriage, a series of stops adjustable to fixed positions in the path of the carriage, and one key for each of said stops, each stop being operable by a key to arrest the carriage when said stop in the carriage is in line with said group.
22. In a typewriting machine, the combination with a carriage carriage, of a stop adjustable in a plurality of two dimensions on said carriage, and key controlling said stop arranged in a series of groups, arranged to be selectively projected transverse to the path of the carriage to intercept said stop in the escapement.
23. In a typewriting machine, the combination of a power-driven carriage, an escapement mechanism for controlling the letter-feed movement of the carriage, means for releasing the carriage from the escapement mechanism to permit the carriage to run from one column position to another, a stop-carrying member on said carriage comprising openings in each of several lines parallel to the travel of the carriage, a key, and means operated thereby for projecting any selected one of a plurality of stops to cooperate with a stop on said stop-carrying member for arresting the carriage at any selected one of a plurality of decimal positions in any one of the columns beyond that from which the carriage is released, the intervening columns being skipped by the carriage in its travel to the selected column.
24. In a typewriting machine, the combination of a power-driven carriage, an escapement mechanism for controlling the letter-feed movement of the carriage, means for releasing the carriage from the escapement mechanism to permit the carriage to run from one column position to another, a stop-carrying member on said carriage comprising openings in each of several lines parallel to the travel of the carriage, and a plurality of keys, each controlling a plurality of stops for arresting the carriage at successive columns, said stops being positioned to correspond to decimal positions in the column whereby said keys may operate to arrest the carriage at any selected one of a plurality of decimal positions in the column represented by the key after any intervening columns have been skipped.
25. In a typewriting machine, the combination of a power-driven carriage, an escapement mechanism for controlling the letter-feed movement of the carriage, means for releasing the carriage from the escapement mechanism to permit the carriage to run from one column position to another, a plurality of column stops arranged along several lines, one line for each column, said column stops being normally ineffective to arrest the carriage, a series of keys, one for cooperation with the column stops in each line, and a plurality of counter stops controlled by each of said keys whereby the counter stops may be operated to arrest the carriage at any one of a plurality of decimal positions in the selected column.
26. In a typewriting machine, the combination of a power-driven carriage, an escapement mechanism for controlling the letter-feed movement of the carriage, means for releasing the carriage from the escapement mechanism to permit the carriage to run from one column position to another, a plurality of column stops comprising a plurality of counter stops, and a summing mechanism for each column comprising a plurality of counter stops, and a sum-

- ber of keys each of which controls the stopping mechanism for some one column to arrest the carriage at that column after intervening columns have been skipped and also 5 controls the adjustment of that stopping mechanism by a selective actuation of the counter stops to effect the stoppage of the carriage at any one of a plurality of decimal stopping positions in the column controlled by the selected key. 10
27. In a typewriting machine, the combination of a power-driven carriage, an escapement mechanism for controlling the letter-feed movement of the carriage, means 15 for releasing the carriage from the escapement mechanism to permit the carriage to run from one column position to another, and key-controlled means for arresting the carriage at any selected one of a plurality of 20 decimal positions in any one of the columns beyond that from which the carriage is released, said key-controlled means comprising a separate stop for each of said decimal positions, the intervening columns being 25 skipped by the carriage in its travel to the selected column, and there being a single key for determining not only the column at which the carriage is to be stopped, but also the decimal stopping position of the 30 carriage in that column. 28. In a typewriting machine, the combination with a carriage and a series of groups of stops, of a single stop on the carriage for each of said groups, and keys for selectively 35 operating the stops of said groups. 29. In a typewriting machine, the combination with a traveling carriage, of a series of groups of stops, a plate carried by the carriage and provided with rows of 40 seats for column stops, each row being in the same vertical plane with a group of stops, and keys to move said stops into the path of column stops in said seats. 30. In a typewriting machine, the combination 45 with a traveling carriage, of a plate carried thereby and provided with rows of seats for column stops, said rows being parallel with the direction of the carriage travel, a series of groups of stops, each 50 group comprising stops arranged in a row parallel with and in the same vertical plane with a row of said seats, and a single operating key for each group operable to selectively project the stops into the path of 55 column stops in the corresponding row. 31. In a typewriting machine, the combination 60 with a carriage, of vertically movable stops arranged in horizontal rows, a column stop for each of said rows and key levers 65 extending beneath the respective rows of stops and each shiftable laterally to operative position relatively to any selected stop in its row and operable from such position to actuate the selected stop into position to 70 intercept its column stop. 32. In a typewriting machine, the combination with vertically movable stops arranged in horizontal rows, of a column stop associated with each of said rows, key levers of the first class having keys at their forward ends and their rear ends extending beneath the respective rows of stops, each of 75 said keys being shiftable laterally to bring its lever in register with any selected stop in its row and depressible to lift the selected stop into position to intercept its associated column stop. 33. In a typewriting machine, the combination with a carriage, of groups of vertically movable stops, each group being arranged in a horizontal row, key levers for 80 said groups, each lever movable laterally into position to coöperate with any selected stop of its group, and movable vertically to project said stop, and stops on the carriage 85 coöperating with said groups of stops. 34. In a typewriting machine, the combination with a carriage, of a bank of keys, groups of stops, one group for each key, the 90 keys being movable horizontally independently of one another to positions to selectively operate the stops, and movable vertically from such positions to actuate the stops, means to prevent lateral displacement of the levers during such vertical movement, 95 and column stops on the carriage in position to intercept the actuated stops. 35. In a typewriting machine, the combination with a carriage and a series of column stops, of a series of keys, one for each 100 column stop, a series of decimal stops for each key, whereby when any key is operated, the carriage is arrested in the column corresponding with the operated key, and means for enabling each key to determine which decimal stop shall be operated and thereby determine at which of several decimal positions the carriage shall be arrested in said column. 105 36. In a typewriting machine, the combination with a carriage and a series of column stops, of a series of keys, one for each column stop, whereby when any key is operated, the carriage is arrested in the column corresponding with the operated key, a series of decimal stops for each key, and means for enabling each key to select one of its associated decimal stops to determine at which of several decimal positions the carriage shall be arrested in said column, said key being movable laterally for selecting the decimal stop whereby to arrest the carriage, and being depressible for releasing the carriage and projecting the associated decimal stop. 110 115 37. In a typewriting machine, the combination with a carriage and a series of column stops, of a series of keys, one for each column stop, a series of decimal stops for each key, means operated by each key to release the carriage and permit it to run for 120 125 128

ward to the corresponding column, and means controlled by the position of the operated key at the time the carriage is released to selectively project one of its associated decimal stops, to determine at which of several decimal positions the carriage shall be arrested in said column.

38. In a typewriting machine, the combination with a carriage and a series of column stops, of a series of keys, one for each column stop, a series of decimal stops for each key, the keys movable in a horizontal direction to selectively determine which of its decimal stops shall be projected and thereby determine at which of several decimal positions the carriage shall be arrested in a column, and means operated by depressing the keys to release the carriage and

bring it to the column corresponding to the operated key.

39. In a typewriting machine, the combination with a carriage and a series of column stops, of a series of keys, one for each column stop, said keys each movable laterally to selectively determine at which of several decimal positions the carriage shall be arrested in a column, said keys movable vertically, rows of key-operated stops, one row for each key, and means operated by the vertical movement of a key to release the carriage and project a stop into the path of the corresponding column stop.
